(57) **CLAIM**

The ornamental design for a tail plane for a helicopter, as shown and described.

DESCRIPTION

FIG. 1 is a perspective view of a tail plane for a helicopter according to a first embodiment of our new design;

FIG. 2 is a front elevation view thereof;

FIG. 3 is a left-side elevation view thereof;

FIG. 4 is a rear elevation view thereof;

FIG. 5 is a right-side elevation view thereof;

FIG. 6 is a top plan view thereof;

FIG. 7 is a bottom plan view thereof;

FIG. 8 is a perspective view of a tail plane for a helicopter according to a second embodiment of our new design;

FIG. 9 is a front elevation view thereof;

FIG. 10 is a left-side elevation view thereof;

FIG. 11 is a rear elevation view thereof;

FIG. 12 is a right-side elevation view thereof;

FIG. 13 is a top plan view thereof; and,

FIG. 14 is a bottom plan view thereof.

The broken lines illustrating a helicopter are for environmental purposes only and form no part of the claimed design.
